UNITED STATES PATENT OFFICE.

FREDRICK A. THURSTON, OF LYNN, MASSACHUSETTS.

BUFFING-MACHINE.

1,218,339.

Specification of Letters Patent.

Patented Mar. 6, 1917.

Application filed December 21, 1914. Serial No. 878,271.

To all whom it may concern:

Be it known that I, FREDRICK A. THURSTON, a citizen of the United States, residing at Lynn, in the county of Essex and State of Massachusetts, have invented new and useful Improvements in Buffing-Machines, of which the following is a specification.

This invention relates to a machine for buffing articles of sheet material and is especially adapted to buff shoe counters and toe caps. Said shoe counters are made of different materials, including leatherboard and they are hard and difficult to bring to an even beveled edge. They are first submitted to a skiving machine which skives off the edges of the articles at an angle and then are subsequently run through a buffing machine to still further reduce the edges of the article in thickness and to smooth off the roughnesses left by a skiving machine.

The invention relates particularly to the construction of the pad used in connection with a roll or movable feed member, whereby the counter or toe cap is held in contact with a sand paper covered buffing roll which also constitutes a feed roll.

The object of the invention is to buff the entire skived portion of the counter or toe cap at a single operation, both the ends and sides of said counter or toe cap.

The invention consists particularly in the improved pad for buffing articles of sheet material and in the combination of said pad with a rotary member, all as hereinafter set forth in the specification and particularly pointed out in the claims.

Referring to the drawings:

Figure 1 is an end elevation of a pair of feed rolls embodying my invention, the table upon which the counters or toe caps are placed preliminary to feeding them between the rolls being shown in section.

Fig. 2 is a sectional elevation taken on line 2—2 of Fig. 1 showing a counter in position between the rolls.

Fig. 3 is a sectional view taken on line 3—3 of Fig. 2.

Fig. 4 is a plan view of my improved pad, a portion of a counter being shown thereon in full lines and broken away, the portion of said counter broken away being shown in dotted lines.

Fig. 5 is a section taken on line 5—5 of Fig. 4, with the counter shown complete.

Fig. 6 is a plan view of a pad particularly adapted for a toe cap, a portion of a toe cap

being illustrated on said pad and broken away, the remaining portion of said toe cap being indicated by dotted lines.

Fig. 7 is a section taken on line 7—7 of Fig. 6 with the toe cap shown complete.

Like numerals refer to like parts throughout the several views of the drawings.

In the drawings, 6 and 7 constitute a pair of feed rolls which are rotated in the direction of the arrows thereon by suitable mechanism. The feed roll 6 is covered with an abrasive material, such as sand paper, 8, and constitutes not only a feed roll, but a buffing roll as well. 9 is a table upon which are placed the counters preparatory to feeding them between the feed rolls.

The feed roll 7 constitutes a rotary feed member embodying a holder 10 which comprises a center piece 11 with segmental blocks 12 fast thereto. These segmental blocks are formed of wood and each has in its outer face a recess 13 adapted to receive a pad 14 of rubber. These pads have vulcanized on their inner faces pieces of textile material 15, such as canvas, and the canvas is fastened by adhesive material to the segmental wooden blocks 12, thus firmly fastening the rubber pads 14 to the segmental blocks 12. There is, preferably, a space 16 between the inner faces of the pads 14 and the outer surface of the holder, each of the wooden blocks 12 forming a portion of said holder. This space 16 extends longitudinally of the feed member 7 and is for a purpose hereinafter set forth. When the pads are in position it will be seen that they are curved on the arc of a circle concentric with the center of the holder 10 and that said rubber pads form the periphery of the feed member 7; being so constructed and positioned as to engage the periphery of the roll 6. The roll 6 is held in frictional engagement with the feed member 7 in a manner well known to those skilled in the art.

The pads 14 (Figs. 1 to 5 inclusive) are made of two kinds of rubber, the central portion 28 thereof being formed of soft rubber, whereby said portion of said pad is rendered relatively more yielding than the portion 29 which is formed of comparatively hard rubber. The object of this construction of the pad is to allow the thick portion 18 of a counter 19 to sink into the pad, while the thin "feather" edges 20 of said counter which extend entirely therearound on one face are held firmly against the abrasive

surface 8 of the roll 6 during the buffing operation—that is, the end portions and the side portions of the counter are skived on a skiving machine before the counter is brought to the buffing machine and are skived at an angle or beveled as seen in Fig. 4, and in the machine of my invention the counter is run between the rolls 6 and 7 in order to buff the same over one entire surface, including the thick portion 18 and the skived portions 20, and it is the object of this invention to enable counters of different sizes and shapes to be buffed over the entire surface by running them between the rolls 6 and 7.

By making that portion 28 which corresponds to the thickest portion of the counter of soft rubber and by making the remainder 29 of the pad of relatively hard rubber—that is, by making that portion of the pad over which the skived portion of the counter projects of hard rubber and vulcanizing the two said portions together, it will be evident that the thick portion of the counter will be forced into the pad, said pad being made yielding throughout the portion 28 to allow said thick portion of the counter to be forced thereinto, while the thin skived portions of the counter are firmly held up against the abrasive surface of the roll 6 by the relatively hard portion 29, so that while the portion 28 of the pad will yield to allow the thick portion of the counter to sink therewith during the buffing operation, the beveled portions of the counter will be held firmly against the roll 6 by the portion 29 all in such a manner as to buff the counter over the surface of one side thereof, both skived and thick portions.

Many counters are formed of material which is stiff and unyielding and which will not bend laterally thereof, and as the counters are fed between the rolls it is desirable that there should be a space between the inner surface of the pad 14 and the outer portion of the block 12 of the holder 10, so that this space allows the rubber pad to yield bodily downward, as illustrated in Fig. 2, when the counter is passing through between the rolls, thus the yielding necessary to allow the counter to pass between the rolls and be buffed without being injured need not depend entirely upon the construction of the pad with its relatively soft portion 28, but may depend partly upon the pad yielding bodily to enter to a certain extent the space 16.

Referring to Figs. 6 and 7, 21 is a pad formed of two kinds of rubber, similar to the pad 14, the central portion 22 being formed of soft rubber and the outer portion 23 being formed of comparatively hard rubber and these portions are vulcanized together so as to become practically integral with each other and to form a pad in which

the article to be buffed, such as a toe cap 24, which has a skived outer portion 25 and a comparatively thick central portion 26, is allowed to yield when it is being passed through between the feed rolls, so that the thick central portion 26 may be embedded in the soft rubber portion 22 while the outer skived portions 25 of the toe cap are firmly held up against the roll or against the abrasive surface 8 of the sand paper roll and are buffed.

The lines 27 Figs. 4 and 6 indicate approximately the line of division between the soft and hard rubber portions of the pads and it will be seen that the skived portions 25 of the counter and toe cap extend outwardly over the hard portions 29 and 23, respectively, of the rubber pads 14 and 21.

The general operation of the mechanism hereinbefore described is as follows: The counters are placed upon the table 9 in a manner well known to those skilled in the art and fed in between the rolls 6 and 7. The skived portion 20 of the counter passes between the rolls 6 and 7 and is buffed by the abrasive surface 8 of the roll 6 and said skived portion is held firmly against the sand paper surfaced roll during the buffing operation, while the thick portion of said counter is also firmly held against said roll, but the pad 14 yields, due to the soft portion 28 thereof, to allow said thick portion to pass through between the rolls without forcing the sand paper roll away from the feed roll 7 and from the pad 14 to such an extent as to render the buffing of the skived portion of the counter ineffective.

Substantially the same operation and result is obtained by feeding the toe caps through and employing a pad 21.

It will be understood that the said soft and hard rubber pads may be used either for counters or toe caps by making the soft rubber portion of the proper extent and outline to allow the thick portion of the counter or toe cap to be embedded therein, as hereinbefore described. The result of the combined yielding of the soft rubber portion of the pad and to a certain extent the bodily yielding downward of said pad into the space 16 is that the counter or toe cap is evenly buffed throughout its entire extent.

As shown in the drawings, the counters or toe caps are fed through between the rolls sidewise thereof, but they may be fed lengthwise thereof, if desired, in which case the pads would be extended around the roll longitudinally instead of laterally.

In general the mechanism hereinbefore described is similar in certain respects to the mechanism shown and described in my co-pending application Serial No. 752,536, filed March 7, 1913, but the pad differs therefrom in that it is adapted to allow a

counter to be fed between one pair of rolls and to buff the entire surface of the counter, whereas in the invention embodied in said co-pending application the use of two pairs of rolls is contemplated and the buffing of the opposite ends of the counter only.

Having thus described my invention, what I claim and desire by Letters Patent to secure is:

- 10 1. A rotary feed member for buffing machines having a pad on its periphery consisting of a central portion of yielding material and an outer portion of relatively harder material surrounding said central portion.
- 15 2. A rotary feed member for buffing machines having a pad on its periphery consisting of a central portion of soft rubber and an outer portion of hard rubber surrounding said central portion.
- 20 3. A pad for machines for buffing articles of sheet material consisting of a central portion of yielding material and an outer portion of relatively harder material sur-

rounding said central portion, said central portion being of such size and contour as to be entirely covered by said article while the edges of said article project onto said surrounding harder portion.

4. A pad for machines for buffing articles of sheet material consisting of a central portion of yielding material and an outer portion of relatively harder material surrounding said central portion, said central portion being of such size and contour as to be entirely covered by said article while the edges of said article project onto said surrounding harder portion, said central portion being of substantially the contour but of less area than the area of the article to be buffed.

In testimony whereof I have hereunto set my hand in presence of two subscribing witnesses.

FREDRICK A. THURSTON.
